(57) **CLAIM**

The ornamental design for a home personal computer cabinet, as shown and described.

DESCRIPTION

FIG. 1 is a front elevational view of a home personal computer cabinet showing my new design;

FIG. 2 is a front elevational view thereof showing the doors in an open position and a drawer/desk in a retracted position; FIG. 3 is a cross-sectional view taken along line 3—3 of FIG. 1;

FIG. 4 is a left side elevational view thereof, the right side elevation view being a mirror image thereof;

FIG. 5 is a top plan view thereof;

FIG. 6 is a cross-sectional view taken along the line 6—6 of FIG. 1, and showing in broken lines, for illustrative purposes only and forming no part of the claimed design one of the doors in an opened position;

FIG. 7 is a rear elevational view thereof;

FIG. 8 is a side elevational view thereof with the doors and drawer in an open position;

FIG. 9 is a perspective view thereof; and,

FIG. 10 is a perspective view thereof with the doors and drawer in an open position.
